UNITED STATES PATENT OFFICE.

WILLIAM J. A. KUEHL, OF CHICAGO, ILLINOIS.

RECEPTACLE.

1,126,789.

Specification of Letters Patent.

Patented Feb. 2, 1915.

Application filed February 16, 1914. Serial No. 818,391.

To all whom it may concern:

Be it known that I, WILLIAM J. A. KUEHL, a citizen of the United States, and a resident of the city of Chicago, county of Cook, and State of Illinois, have invented certain new and useful Improvements in Receptacles, of which the following is a specification.

My invention relates to improvements in receptacles especially adapted for containing poison and has for its object the provision of improved means for preventing accidental taking of poison.

The invention consists in the combinations and arrangements of parts hereinafter described and claimed.

The invention will be best understood by reference to the accompanying drawing forming a part of this specification, and in which—

Figure 1 is a section taken through the neck of a bottle provided with a closure embodying my invention, Fig. 2, an enlarged section through the closure, Fig. 3, a section taken on line 3—3 of Fig. 2, and Fig. 4, a top plan view corresponding to Fig. 3.

The preferred form of construction as illustrated in the drawing comprises an ordinary bottle 5 having an annular recess 6 formed in its neck and having a locking shoulder 7 therein. A closure 8 is inserted within the mouth of the bottle and is provided with an ordinary cork 9 which seals the bottle. The closure 8 carries spring held locking dogs 10 which project outwardly through notches 11 in the walls thereof and are adapted to engage under shoulder 7 and thus detachably lock closure 8 in position. These locking dogs carry upwardly extending arms 12 to which are attached pins 13 which project outwardly through suitable openings in the walls of closure 8 above the mouth of the bottle as shown. A spring 14 serves to hold dogs 10 normally in engagement with shoulder 7. By this arrangement it will be observed that the closure 8 and cork 9 will be detachably locked in position and can only be released by pressing pins 13 inwardly or by destruction of the bottle.

A combination lock dial 15 is arranged in the top of closure 8 and carries a knob 16 for manipulating the same. Dial 15 is permanently locked in position by means of a stem 17 which is riveted to the bottom of closure 8. A combination plate 18 is formed integral with the bottom of dial 15 and is

formed with diametrically disposed notches 19 which are adapted to receive arms 12 and with a segmental notch 20 as shown in Fig. 3. Another combination plate 21 is loosely mounted on stem 17 immediately below plate 18 and is provided with diametrically disposed notches 22 adapted to receive arms 12. The bottle is provided with an upwardly extending pin 23 which engages within notch 20 and permits of limited movement between plate 21 and plate 18 but compels said plates to move together after such limited movement has taken place. Arms 12 contact with the periphery of plate 21 so as to exert friction on said plate and thus prevent movement of said plate with plate 18 except when the pin 23 has reached one end or the other of notch 20. By this arrangement it will be observed that the closure can only be removed from the bottle by properly setting the plates 18 and 21 with notches 19 and 22 in registration with arms 12. This can only be done by one knowing the combination indicated on dial 15, thus preventing the accidental taking of the contents of the bottle.

The closure 8 is provided with a depending socket 24 and the upper end of cork 9 is fitted within said socket, tangs 25 at the lower edge of said socket being pressed into said cork so as to permanently secure the same in position. This constitutes a simple and effective means for removing the cork with the closure and also provides a tight seal from the bottom.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A receptacle having a mouth and a locking shoulder within the same, a closure fitting in said mouth, normally projected locking dogs in said closure arranged to engage said shoulder, means outside of said closure for retracting said dogs, and a permutation lock arranged to prevent with-

drawal of said dogs except when properly set.

2. A receptacle having a mouth and a locking shoulder within the same, a closure fitting in said mouth, spring held locking dogs in said closure arranged to engage said shoulder, means outside of said closure for retracting said dogs, and a permutation lock comprising two rotatable notched disks ar-

ranged to prevent withdrawal of said dogs except when properly set.

In testimony whereof I have signed my name to this specification in the presence of two subscribing witnesses.

WILLIAM J. A. KUEHL.
